UNITED STATES PATENT OFFICE

93,144

DESIGN FOR A CATHOLIC MASS PRAYER CLOCK DIAL OR SIMILAR ARTICLE

Joseph F. Stedman, Brooklyn, N. Y.

Application May 19, 1934, Serial No. 51,847

Term of patent 14 years

To all whom it may concern:

Be it known that I, JOSEPH F. STEDMAN, a citizen of the United States, residing at Brooklyn, in the county of Kings, and State of New York, have invented a new, original, and ornamental Design for a Catholic Mass Prayer Clock Dial or Similar Article, of which the following is a specification, reference being had to the accompanying drawing, forming part thereof.

Figure 1 is a face view showing my new design, and

Figure 2 is an edge elevation of the same.

I claim:

The ornamental design for a Catholic mass prayer clock dial or similar article, as shown.

JOSEPH F. STEDMAN.
